United States Patent Office

Des. 183,680
Patented Oct. 14, 1958

183,680

COMBINED POCKETBOOK AND BILLFOLD

Herbert S. Chase, Flushing, N. Y., assignor to Bernard Cahn Co., Inc., New York, N. Y., a company

Application June 6, 1956, Serial No. 41,784

Term of patent 14 years

(Cl. D87—3)

Fig. 2 is a perspective view thereof in open position; and

Fig. 3 is a rear elevational view of Fig. 1.

I claim:

The ornamental design for a combined pocketbook and billfold, substantially as shown.
